UNITED STATES PATENT OFFICE

2,005,319

OPPOSED RECIPROCATORY TOOL
MACHINEHarry M. Johnston, McKeesport, Pa., assignor to
National Tube Company, a corporation of New
Jersey

Application October 17, 1932, Serial No. 638,246

5 Claims. (Cl. 77—3)

This invention relates to opposed reciprocating tool machines. One of the objects is the provision of a machine which operates in a semi-automatic manner. Other objects may be inferred from the following disclosure of a specific form of the invention.

Referring to the accompanying drawings—

Figure 1 is a top plan.

Figure 2 is a side elevation.

10 Figure 3 is an enlarged cut away side elevation.

Figure 4 is an end elevation.

Figure 5 is an end elevation showing the one opposite that of Figure 4.

Figures 6 and 7 are enlarged details.

15 Figure 8 is an enlarged detail showing one type of tool working a pipe coupling.

A hollow base 1 carries housings 2 and 3 interconnected by a bridge 4. These housings mount the reciprocative tools and the bridge forms the upper support for a vise means holding pipe 20 couplings therebetween. The vise means includes an upper jaw member 6 carried by a piston 7 fitted in a cylinder 8 carried by the bridge 4 and a fixed lower jaw 6^a. This cylinder and bridge 25 are here formed by a single casting to provide structural simplicity.

A track or slide 9 is carried by a pair of cylinders 10 fitting vertical guiding pistons 11 fixed to the base 1. This slide extends horizontally 30 from the machine in alignment with the jaw members and has a slotted end fitting around the fixed lower one of the latter. That is to say, the track or slide 9 rises and lowers on a horizontal plane and has an end encompassing the 35 lower jaw member of the vise means.

This slide mounts a carriage 12 consisting of two parallel arms interconnected at one end by a handled cross-member 13 and constructed with laterally aligned coupling depressions. This carriage is arranged so that its arms may slide by 40 both sides of the fixed jaw member 5.

The jaw members are here constructed to hold two couplings at once so that the movable member 6 is centrally pivoted to its actuating piston 7 to insure equal pressure on both couplings. This piston is connected by rods 14 to the two cylinders 10 carrying the slide 9 so that when the movable jaw is forced into coupling engaging position the carriage 12 will be pushed well 45 below the level of the fixed vise member. A constant pressure is maintained in the cylinders 10 so that the slide 9, carriage 12 and upper movable jaw member 6 are urged upwardly.

The couplings are loaded in the depressions on 55 the carriage 12 when the latter is pulled to the outermost limits of the slide 9. The carriage is then pushed into the machine and pressure applied to the cylinder 8. This forces the movable jaws 6, slide 9 and carriage 12 downwardly. The couplings then are engaged by the vise means

and freed from the carriage which may be pulled to its outermost position so that two more couplings can be loaded thereon.

As soon as the couplings in the machine are completely worked the pressure is released from the cylinder 8 and the movable jaws, slide and carriage are forced upwardly by the pressure in the cylinders 10. The carrier 12 is again pushed into the machine and its ends engage the two couplings already there and push them out of the 10 way so that the two new loaded couplings may be positioned for engagement by the vise means.

The above loading operation may be performed very quickly. The moment the loaded carriage 12 is shoved into the machine pressure may be 15 applied to the cylinder 8 to clamp the couplings. This will automatically push the slide to a downward position and permit removal of the carriage 12 which may be immediately reloaded.

The tool reciprocating mechanism is carried 20 by the housings 2 and 3. It includes two pairs of opposed reciprocating spindles 15. These rotate in antifriction bearings carried by mounts 16 which slide in guide sleeves 17. The innermost ends of these spindles carry tools suitable to 25 shape the couplings held by the vise means previously described. It might be mentioned that these couplings are in the usual blank form which must be shaped for tapping. The means accomplishing this consist merely of cutting tools suitably 30 clamped to the spindles 15.

The two spindles on each side of the machine are driven by shafts 18 having long pinion ends 19 to which the spindles are connected by spur-gears 20. In each instance the adjacent spur-gears are set out of alignment to provide room for each. The shafts 18 are both geared to a common drive-shaft 21 which receives its power from a motor 21^a through a suitable flexible coupling. This shaft is illustrated as consisting of two 35 separate parts interconnected by a flexible coupling. The shaft 21 is connected to the drive-shafts 18 by heavy spur-gears 22.

As so far described, the machine includes rotatively driven reciprocating tool spindles. In addition, the machine includes a mechanism for feeding these spindles quickly up to working position and then at a slower and proper working speed. When the tools have finished their work 40 this mechanism quickly withdraws them and permits operation of the vise means as described.

This mechanism includes a two-arm lever 23. The lower arm of this lever is fixed to the two left-hand spindles. A one-arm lever 24 is fixed to the two right-hand spindles and to the upper arm of this lever 23 by a connecting-rod 25. When the two-arm lever 23 is reciprocated the opposed spindles will move in opposite directions.

45 A ratchet-wheel 26 is arranged adjacent this 50

lever 23 and is continually driven in one direction. In the present instance it is driven by the motor 21. The connection is made by a gear train 27 driven by the left-hand drive-shaft 18 and driving the ratchet-wheel 26 through a worm gearing 28. This drive is finally effected through a slip clutch 29.

The ratchet-wheel 26 and the gear driven by the worm are freely mounted on a shaft 30 which also fixedly mounts an arm 31. This arm is connected to the two-arm lever 23 by a link 32. The end of the shaft 30 also mounts a second arm 33 adjacent the ratchet-wheel 26. A shaft 34 interconnects the ends of these two arms. As the arm 31 is outside of the housing 2 and the arm 33 is inside, it is necessary to construct the housing with an arcuate slot 35 through which the shaft 34 passes.

The end of the shaft 34 adjacent the ratchet-wheel 26 carries a dog 36 which engages therewith when urged by a spring 37 which, in the present instance, is arranged at the outside end of the shaft. This shaft also fixedly carries a cam faced lever 38 on its outside end. This cam faced lever is arranged to turn the shaft 34 so the dog 36 is thrown out of engagement with the ratchet-wheel 26.

The gear train 27 is arranged to drive the ratchet-wheel so that when engaged by the dog 36 the arm 31 will be turned in a direction which will move the spindle interconnecting system in a direction causing the tools to feed into the work. When the arm 31 is oppositely moved this spindle interconnecting system will be moved in a direction causing the separation of the spindles.

An air cylinder 39 in which a plunger 40 is fitted is arranged to push the arm 31 in a direction which will feed the spindles together. The stroke of the plunger is controlled by a backwardly extending rod 41 provided with an end which engages spacers 42. These spacers are removable and may be substituted by others of different sizes.

A second air cylinder 43 opposes the cylinder 39 and has a plunger 44 which moves the arm 31 in a direction to separate the spindles. In the present instance this plunger consists of inner and outer sliding parts. The inner part having the greater area begins its movement first and is arranged to engage the cam surface of the lever 33 to disengage the dog 36. The outer part then comes in engagement with the arm 31, moves as a unit with the inner one and causes the spindles to separate.

Preferably, the cylinders 8 and 29 are connected to an air line through a valve 45. This valve is constructed to simultaneously admit air to both the cylinders when thrown in one direction. The cylinder 43 may also be connected to this valve. This valve may be further constructed so that when thrown in an opposite direction it will simultaneously exhaust the cylinders 8 and 39 and admit pressure to the cylinder 43. The arm 31 may be provided with a projecting end 46 which engages adjustable stops 47 at both extremes of its movement. This provides a means for limiting the reciprocating extremes of the spindles. When this stoppage occurs the friction clutch 29 will slip.

Although a specific form of this invention has been shown and described in accordance with the patent statutes, it is not intended to limit its

scope exactly thereto, except as defined by the following claims.

I claim:

1. In a machine including opposed reciprocating tools, a downwardly movable upper jaw and a fixed lower jaw arranged between said tools, a depressible horizontal slide extending away from said jaws and having a slotted end fitting around said fixed lower jaw, a carriage carried by said slide and having parallel arms constructed to slide by both sides of said fixed lower jaw and in which there are laterally aligned coupling-receiving depressions, means for urging said slide upwardly, means for interconnecting said downwardly movable upper jaw and said slide, and means for forcing said upper jaw downwardly so that said slide is moved downwardly against the urge of the first named means. 15

2. The combination of opposed reciprocating tools, a fixed lower jaw, an upper jaw arranged for clamping action against said lower jaw, said jaws being arranged to hold work between said tools, a downwardly movable track or slide transversely associated with said lower jaw, and a carriage riding said track or slide and constructed to carry work to a position between said jaws so that downward movement of said track or slide will cause said work to be deposited on said lower jaw. 20

3. The combination of opposed reciprocating tools, a fixed lower jaw, an upper jaw arranged for clamping action against said lower jaw, said jaws being arranged to hold work between said tools, a downwardly movable track or slide transversely associated with said lower jaw, and a carriage riding said track or slide and constructed to carry work to a position between said jaws so that downward movement of said track or slide will cause said work to be deposited on said lower jaw, and means for interconnecting said upper jaw and said track or slide for mutually dependent movement, whereby clamping action of said upper jaw will cause said downward movement of said track or slide. 35

4. The combination of opposed reciprocating tools, a fixed lower jaw, an upper jaw arranged for clamping action against said lower jaw, said jaws being arranged to hold work between said tools, a downwardly movable track or slide transversely associated with said lower jaw, a carriage riding said track or slide and constructed to carry work to a position between said jaws so that downward movement of said track or slide will cause said work to be deposited on said lower jaw, means for interconnecting said upper jaw and said track or slide for mutually dependent movement, whereby clamping action of said upper jaw will cause said downward movement of said track or slide. 40

5. In a machine including opposed reciprocating tools, a downwardly movable upper jaw and a fixed lower jaw arranged between said tools, a depressible horizontal slide extending away from said jaws and having a slotted end fitting around said fixed lower jaw, and a carriage carried by said slide and having parallel arms constructed to slide by both sides of said fixed lower jaw and in which there are laterally aligned coupling-receiving depressions. 65

HARRY M. JOHNSTON.
